KEY HOLDER

Edwin G. Dimond, Flint, Mich.

Application August 6, 1949, Serial No. 109,023

2 Claims. (Cl. 150—40)

1

This invention relates to a key holder, and has especially to do with a key case in which the keys are suspended by means of elastic members.

In key cases of conventional design, where the keys are suspended in the case by means of threaded studs and sleeves or metal spring clips, the keys very often become lost by reason of the breaking of the spring clip or by the loosening of the studs holding the keys. The use of metal clips for supporting keys in a key case is also objectionable because the clips and the keys invariably become entangled with one another and offer considerable difficulty to the user who attempts to select a particular key for use. In key cases formed of leather or other pliable material, the use of metal fasteners and metal key clips imparts to the key case, after a relatively short time, an unsightly shape and appearance, and the metal parts often become exposed and cause wear on the pockets of the user.

It is an object of this invention to provide a key holding member of elastic material which is arranged to snugly embrace the head of a key and thereby retain it in a manner in which the key is unlikely to become loosened or lost. More specifically, the invention contemplates a key holding device in the form of a rubber cap which is arranged to be stretched over the head of a key for suspending the key in a key case.

Another object of this invention resides in the provision of a key case in which the keys are supported by flexible and preferably elastic members which are relatively self-supporting and which, therefore, tend to maintain the keys in an orderly fashion within the case.

A further object of the invention concerns the provision of a key case made of rubber, which is adapted to maintain its shape, the case being characterized by the provision of rubber fastening means for closing the case as well as for supporting the keys in the case so that the objectionable features associated with key cases having metal fasteners are eliminated in a key case of my construction.

Other objects and advantages of the invention will become apparent from the following description taken in conjunction with the accompanying drawings in which:

Figure 1 is a perspective view of a key case of my invention with a cover for the case in the open position.

Figure 2 is a vertical sectional view of a key case.

Figure 3 is a sectional view taken along the lines 3—3 in Figure 2.

2

Figure 4 is a sectional view taken along lines 4—4 in Figure 2 showing more particularly the key supporting members of my invention.

Referring to the drawings, the key case comprises a flat rectangular container, generally indicated as 10, having side walls 12, top and bottom walls 14 and 15, respectively, a rear wall 16, and an opening 17 at the front face thereof. Container 10 is preferably formed as molded rubber and has a cover member 18 which closes opening 17 and forms a front wall for the container. Cover 18 is connected along one edge with the front edge of bottom wall 15 as at 20. Along its opposite free edge cover 18 is provided with a flap member 22 which projects from the inner face of the cover and is arranged to overlie top wall 14 of container 10. Along its free edge, flap 22 is provided with a depending flange 24 which, when the cover is in the closed position, engages behind rear wall 16 along the upper edge thereof, as is best shown in Figure 2. Cover 18 may be secured to container 10, as at 20, by a suitable rubber adhesive.

Cover 18 and container 10 are preferably molded from a rubber of sufficient hardness so that they will be relatively self-supporting and will retain their shape. Under such circumstances, cover 18 will normally tend to remain in or return to the closed position. The case may be opened by simply disengaging flange 24 from behind rear wall 16 and bending the cover forwardly and downwardly so as to expose the interior of the container.

Within the container and at the upper end thereof, there is secured by a suitable adhesive a support bar 26 which is also formed of rubber. Bar 26 is of fairly heavy construction and reinforces case 10 at the upper portion thereof. Keys 28 are arranged to be suspended from bar 26 by means of flexible suspension members 30. Members 30 are preferably molded integrally with bar 26, but, if desired, may be secured thereto by adhesive. Members 30 are preferably arranged in two spaced rows, one behind the other, the members in one row being staggered with reference to the members in the other row.

At their lower ends, the suspension members are each provided with an elastic cap member 32 which in the unstretched condition are dimensioned smaller than the head of a key. Caps 32 may be enlarged by stretching so as to enable the head of a key to be inserted therein. In order to prevent the keys from falling out of caps 32, the caps are provided with an opening 34 at the lower end thereof which is smaller in

size than the internal dimension of the cap above the opening. When the cap is stretched over the head of a key, the mouth of the cap is adapted to engage the edge portions of the head of the key which converge into the key shank 36. Members 30 are dimensioned such as to be self-supporting so that they normally tend to maintain the keys within the case in an orderly aligned fashion.

When it is desired to use one of the keys within the case, the user simply disengages flange 24 from behind wall 16 and bends cover 18 downwardly to the open position shown in Figure 1. Then with the same hand, he can select the proper key and pull it outwardly to stretch and bend the member 30 by which the key is suspended from within the case. It will be noted that the entire operation can be performed with one hand thus leaving the other hand free for carrying packages and the like. When the key is released, member 30 automatically springs back to the straight position and the key is returned to its normal position within the case.

It will thus be seen that I have provided a key case which is convenient to use and in which the use of metal fastening devices is completely eliminated. By forming the case out of a rubber of sufficient hardness to remain relatively stiff, it will be appreciated that the case will not become distorted in time so as to present an unsightly appearance. It will also be noted that the provision of rubber suspension members 30 prevents the keys from becoming entangled within the case and facilitates the ready selection of the desired key. At the same time, rubber caps 32 insure against loss of the keys and maintain the keys in an orderly fashion within the case. Caps 32, it will be noted, are readily stretchable so as to accommodate keys having heads of different sizes and shapes.

I claim:

1. In a key case including a container, the

combination of a supporting member within said container extending along and secured to one end of the container, said supporting member having a plurality of integral fingers depending therefrom, said fingers extending in parallel, spaced relation and being formed of a resilient material which is sufficiently rigid and self-supporting to maintain said fingers in said parallel, spaced relation, and means integrally connected with the free ends of said fingers for fixedly holding a key, whereby said fingers and the said key holding means tend to maintain the keys in an orderly, aligned position within said container.

2. The combination set forth in claim 1 wherein in said key holding means comprises cap members integrally connected with the free ends of said fingers, said cap members being formed of an elastic material and being dimensioned in the unstretched condition smaller than the head of a key to be retained thereby.

EDWIN G. DIMOND.
